(No Model.)

C. J. GALLOWAY & J. H. BECKWITH.
WATER TUBE BOILER.

No. 442,036.

Patented Dec. 2, 1890.

UNITED STATES PATENT OFFICE.

CHARLES J. GALLOWAY AND JOHN H. BECKWITH, OF MANCHESTER,
ENGLAND.

WATER-TUBE BOILER.

SPECIFICATION forming part of Letters Patent No. 442,036, dated December 2, 1890.

Application filed August 27, 1890. Serial No. 363,194. (No model.) Patented in England May 22, 1890, No. 7,929.

To all whom it may concern:

Be it known that we, CHARLES JOHN GALLOWAY and JOHN HENRY BECKWITH, citizens of England, both residing at Knott Mill Iron Works, Manchester, in the county of Lancaster, England, have invented a new and useful Improvement in Water-Tube Boilers, (for which we have made application for patent in Great Britain, which patent when granted 10 will bear date May 22, 1890, No. 7,929,) of which the following is a specification.

Our invention relates to that class of boilers in which there are two water-chambers connected by a number of tubes around which 15 play the flames and hot products of combustion from the furnace. The water-chambers extend upward above the tubes and open into a common horizontal chamber, affording a water and steam space. Such boilers are 20 usually set so that the tubes which connect the water-chambers are somewhat inclined, in order that the water heated and the steam generated in the tubes shall flow freely along the tubes to their upper ends, and thence up 25 one of the end chambers into the horizontal chamber above, from which the cooler portions of the water descend the other end chamber to pass again through the tubes. There is thus produced a rapid circulation, 30 causing such ebullition and commotion of the water in the upper chamber that the steam as it passes from the chamber is apt to carry water-spray with it.

One of the objects of our invention is to 35 prevent this violent commotion of the water, and we effect this by dividing the upward current by a number of inclined partitions radiating from the mouth of the end chamber, so that the current is divided into a number 40 of separate currents expanding in width and losing velocity as they ascend and flow toward the farther end of the water-space, the steam separating from them gradually and uniformly along the whole length of the chamber. The mouth of the farther water-chamber down which the circulation-current has 45 to descend we raise some distance above the bottom of the horizontal chamber, so that there is in the lower part of the chamber a 50 layer of undisturbed water in which deposit

of impurities can take place, and we provide a blow-off cock by which these can from time to time be blown out.

For the purpose of cleaning the exterior of the water-tubes we utilize the stays of the 55 water-chambers in the following manner: We make these stays tubular, placing them, preferably, in such positions that one of them is in the middle of the space between every three of the water-tubes. Usually the perforations of these stays are closed by plugs or covers to prevent access of air into the flame-chamber; but some of them may be left open to admit air locally for promoting combustion. When it is desired to clear the exterior of the 65 water-tubes from soot or other matter deposited on them, we insert through the perforation of a stay or nozzle, by which we direct a jet of steam on the exterior of the tubes within reach of the jet, and we repeat this at 70 the different stay-openings, the nozzle being connected to a flexible tube, so that the jet can be applied through any of the stays.

Figure 1 of the accompanying drawings is a longitudinal section, and Fig. 2 is an end 75 view, of a boiler embodying our invention.

From the fire A the flames and hot products of combustion are caused by baffle-plates B to take a zigzag course between the tubes, as indicated by the arrows, to the flue leading 80 to the chimney. At the top of the front water-casing C, where it communicates with the steam and water chamber D, we form between inclined diverging plates E a number of expanding passages, dividing the currents of 85 mixed steam and water that ascend from C, gradually retarding the divided streams, and allowing the steam to separate quietly therefrom. At the top of the passage by which the rear water-casing F communicates with the 90 chamber D we provide a part G, raised above the bottom of D, so that impurities may become deposited in the quiescent water below without descending by G to F. These impurities may from time to time be cleared out 95 by opening a blow-off cock or valve applied at H. The stays K of the water-chambers C and F are tubular and preferably so placed that there is one between every three of the tubes T, as shown in Fig. 2. Usually these 100

tubular stays are closed by plugs or covers; or some of them may be left open for admission of air to promote combustion.

For the purpose of clearing soot off the tubes T, we introduce through any of the tubular stays K a nozzle L, connected by a flexible tube to a steam-pipe, so that we can direct a jet of steam along the surface of the tubes within range of the jet, thus sweeping off the matters adhering to them. Obviously, scraping or other tools might also be introduced through the tubular stays.

Having thus described the nature of our invention and the best means we know for carrying the same into practical effect, we claim—

A water-tube boiler having tubular stays for its water-chambers, having a set of divided

expanding passages for the current ascending from the higher water-chamber, and having the mouth of the passage from the lower water-chamber raised above the bottom of the upper chamber, all substantially as and for the purposes herein set forth.

In testimony whereof we have signed our names to this specification, in the presence of two subscribing witnesses, this 11th day of August, A. D. 1890.

CHARLES J. GALLOWAY.
J. H. BECKWITH.
